US00D983928S

(12) **United States Design Patent** (10) Patent No.: **US D983,928 S**
(45) Date of Patent: **** Apr. 18, 2023**

(54) **ATOMIZER FOR INSECTICIDES**

(71) Applicant: **Andermatt BioVet AG**, Grossdietwil (CH)

(72) Inventors: **Adrian Eugster**, Bauma (CH); **Kaspar Schlegel**, Winterthur (CH)

(73) Assignee: **Andermatt BioVet AG**, Grossdietwil (CH)

(**) Term: **15 Years**

(21) Appl. No.: **35/514,404**

(22) Filed: **Dec. 1, 2021**

(80) **Hague Agreement Data**

Int. Filing Date: **Dec. 1, 2021**

Int. Reg. No.: **DM/219345**

Int. Reg. Date: **Dec. 1, 2021**

Int. Reg. Pub. Date: **Jun. 3, 2022**

(51) **LOC (14) Cl.** **22-06**

(52) **U.S. Cl.**

USPC **D22/122**

(58) **Field of Classification Search**

USPC **D22/119, 122-123**

CPC **A01M 13/00; Y10T 137/7468**

See application file for complete search history.
